UNITED STATES PATENT OFFICE.

ALBERT G. HAMBLIN, OF BIG RAPIDS, MICHIGAN, ASSIGNOR OF ONE-HALF TO
ROBERT RITCHIE, OF SAME PLACE.

HEATING-DRUM.

SPECIFICATION forming part of Letters Patent No. 416,601, dated December 3, 1889.

Application filed October 10, 1888. Serial No. 287,764. (No model.)

To all whom it may concern:

Be it known that I, ALBERT G. HAMBLIN, a citizen of the United States, residing at Big Rapids, in the county of Mecosta and State of Michigan, have invented new and useful Improvements in Heating-Drums, of which the following is a specification.

This invention relates to improvements in heating-drums; and it consists in a certain novel construction and combination of devices, fully described hereinafter in connection with the accompanying drawings, and specifically pointed out in the appended claim.

In the drawings, Figure 1 is a side view of the improved drum. Fig. 2 is a central vertical sectional view thereof. Fig. 3 is a horizontal section on the line $x x$ of Fig. 1.

Referring to the drawings by letter, A designates the cylindrical body or casing, which is provided at its upper and lower ends with the upwardly and downwardly convexed heads B and B', respectively, to which are connected the outlet and inlet smoke-pipes C and C'. The body or casing is provided in its side with the hinged door D, which may be opened to enable the interior of the drum to be cleaned when necessary. A series of heating-flues E E are arranged vertically in the body or casing, and extend at their ends through the upper and lower heads of the same around the outlet and inlet pipes. It will be seen that these flues do not communicate with the interior of the body or casing.

F F' F² represent deflectors, which are arranged at intervals in the body or casing, the lower and upper deflectors F and F² being slightly removed at their edges from the sides of the body or casing, and the intermediate deflector F' being provided with a central opening f'. It will be seen that the central opening of the intermediate deflector is out of alignment with the peripheral openings f and f² at the edges of the upper and lower deflectors, and therefore the smoke and other products of combustion in passing through the body or casing are first distributed and caused to pass through the peripheral opening f, then collected and caused to pass through the central opening f', then distributed and caused to pass through the peripheral open-

ing f², and, lastly, they are collected and allowed to escape through the outlet-pipe. This distribution or separation and subsequent collection of the products of combustion are aided by the shapes of the deflectors, the distributing-deflectors being convexed downwardly and the collecting-deflector upwardly.

The above-described manner of directing the passage of the products of combustion through the drum brings the same alternately in contact with the sides of the body or casing and the heating-flues, and therefore when the said products reach the outlet-pipe they have parted with the greater portion of the heat with which they entered the drum.

The effect of heating the flues above mentioned is to heat the columns of air therein and cause currents of air therethrough. The cold air enters the lower ends of the said flues and passes out of their upper ends in a heated condition.

Having thus described the invention, I claim—

The combination, with the heating drum or cylinder having the opposite central smoke-pipes and the annularly-arranged series of openings, those of one head being vertically opposite those of the other head, of the opposite convex and similarly-disposed imperforate deflectors, the diameters of which are less than that of the cylinder, the intermediate deflector concaved and oppositely disposed to the end deflectors, and of a diameter corresponding with that of the cylinder and provided with a central opening and the annularly-arranged series of open-ended cold-air pipes terminating in the openings in the heads of the cylinder and passing through and tightly fitting corresponding openings in the deflectors and serving to support said deflectors in position within the cylinder, substantially as specified.

In testimony that I claim the foregoing as my own I have hereto affixed my signature in presence of two witnesses.

ALBERT G. HAMBLIN.
